OVERHEAD DOOR CONTROL MEANS

Herbert Cady Blodgett, Hartford City, Ind., assignor to Door Control Company, Hartford City, Ind.

Application September 2, 1930. Serial No. 479,179

7 Claims. (Cl. 268—59)

This invention relates to improvements in door control mechanism. It is particularly adapted to the control of an overhead door, that is, a door which passes from a vertical position to a horizontal track overhead, although the mechanism is adapted for use in controlling gates, elevators, and various structures. 5

The objects of the invention are:

First, to provide an improved structure of the 10 class described with a stationary motor.

Second, to provide such a structure with improved electric control.

Third, to provide improved track arrangements with conduits for protecting electric 15 conductors and the like.

Fourth, to provide a structure with an improved safety mechanism to permit the control to run after the door is blocked.

Objects pertaining to details and economies of 20 construction and operation will appear from the description to follow.

A preferred embodiment of my invention appears in the accompanying drawings, in which:

Fig. 1 is a detail elevation assembly view of an 25 overhead door structure with my improved control means installed, the door being shown in cross section and with the hinges between the panels and counterbalance omitted.

Fig. 2 is a plan view of the control means as 30 seen in Fig. 1, the door being omitted.

Fig. 3 is an enlarged detail sectional elevation view taken on line 3—3 of Figs. 2, 4 and 5.

Fig. 4 is an enlarged detail transverse sectional 35 view taken on line 4—4 of Figs. 1, 2 and 3, showing details of construction of the door control carriage to which the overhead door is connected and by which it is operated.

Fig. 5 is an enlarged detail sectional view on 40 line 5—5 of Figs. 1, 2 and 3, showing details of the drive means, the electric motor being omitted.

Fig. 6 is an enlarged detail cross sectional view on line 6—6 of Figs. 1 and 2, showing details of the track and conduit section.

45 Fig. 7 is an enlarged detail perspective view of one of the switch boxes and trips.

Fig. 8 is the wiring diagram for the entire structure.

The parts will be identified by their numerals 50 of reference which are the same in all the views.

1 is an overhead door made up of panels suitably hinged together, the hinges not being shown. 2 is the wall above the door opening. 3 is the track for the door of any usual and well-known 55 form, extended horizontally inward, the inner end

being supported by hanger 31. 4 are the guide pulleys for the counterbalance chain, the counterbalance means and chain being omitted, the same being of such construction as appears in my patent application, Ser. No. 262,309, filed March 16, 60 1928.

5 is the door control carriage. This is supported by a pair of tracks 6, 6', which are channel in form having track grooves in the bottom and being open on their inner sides. The carriage 65 5 is made up of a cross plate 51 which is bent downwardly at the center to form a box-like structure. To the sides of the carriage are secured runners 7, 7 adapted to slide along the tracks 6, 6'. The bracket 53 is provided on the under side of 70 the carriage and is pivotally connected to the bent link 8 which connects to the upper part of the overhead door. The angle in the link permits the carriage 5 to have full travel to the front. 75

The front end of the tracks 6, 6' are joined to a suitable spreader 9 of angle bar which is bolted or otherwise secured to the wall 2. A spreader 10 is also between the opposite inner ends of the rails 6, 6'. The inner ends of the tracks are suitably suspended by hangers 61. 80

The carriage 5 is moved back and forth on the track by endless sprocket chain 11. This is disposed over the idle sprocket wheel 111 carried on bracket 112 secured to the spreader 9 at the 85 outer end and on the driven sprocket 12 carried on shaft 121 carried by the spreader 10 and hanger 13 at the inner ends of the tracks.

The front end of chain 11 is secured by bolt 113 to the lower front part of the carriage 5 and is 90 then arranged upwardly around the sprocket 111 and rests on guide pulley 54 and is then disposed downwardly around the driving sprocket wheel 12 and its rear end is connected to spring bolt 114 carried on bracket 115 on the lower rear part 95 of the carriage 5.

The face of the gear wheel 122 serves as one member of a clutch, being finished flat for that purpose and provided with a friction disk 122'. The opposite member 123 of the clutch is secured 100 to the sprocket wheel 12. Coil spring 124 is on the shaft 121 and holds the sprocket wheel and clutch member 123 yieldingly in contact with the clutch face of the gear 122. The spring is adjustable by the nut 125. Gear 122 is driven by pinion 126 on shaft 127 which is also supported in the hangers 13. Shaft 127 is driven by pulley 128 which is driven by the pulley 151 of motor 15 which is suitably supported by said hangers 13 and 14 on the platform or motor base below. 110

Motor 15 is an alternating current reversible motor capable of driving the pulley in either direction and by this means carrying the carriage 5 back and forth and actuating the door.

5 Carriage 5 is provided with a trip arm 55 which projects above the rail 6 of the track and beyond the same to trip the limiting switches. 16 is the cut-off switch toward the outer end of the track 6, and 17 is the combined cut-off and reverse switch towards the inner end of the track.

The motor 15 is provided with the usual electric construction and connection for reversing comprising tickler coils or like devices. It is controlled by a push button switch 18 and a manual 15 lever cut-off switch 19 as well as by the automatically operated cut-off switch 16 and combined cut-off and reverse switch 17.

The switches are provided with forked trip levers 161 and 171 which are disposed above the 20 track to be engaged by the trip arm 55 as clearly seen in Fig. 4. A lock switch 20 controlled by a suitable key, like a door lock, is provided at the outside. This makes a structure that locks the garage by the mere closing of the door.

25 Wires leading to the motor are disposed in the conduit channel 62 symmetrical with and carried by and associated with the track channel 6. This channel is provided with a cover 63 which is made of an angular piece of sheet metal, the top 64 of which fits the upper side of the channel. At intervals between the channel 6 and the conduit channel 62 are secured flexible retainer strips of metal 65 projecting above and below the channel. These are folded around to retain in place the 35 cover 63 to enclose the conduit 66.

By this arrangement the conductors to the motor and to the various switches are encased and protected.

The switches 16 and 17 are clamped to the conduit by set screws 21 as seen in Figs. 4 and 7. Brackets 22 with channel fillers or closers 23 are secured to the sides of the switch boxes and close the space, effectively enclosing the conductors to the motor and the various switches. This is of 45 importance in protecting the cables.

In the ordinary operation of my structure, starting with the door closed, push button switch 18 is closed and sets the motor in operation, carries the carriage 5 to the right, as seen in Fig. 1, and 50 elevates the door. As soon as the tripping arm 55 strikes the trip arm 161 of the switch 16, the circuit at that point is closed and the push button need no longer be held closed. Because the circuit is closed at that point, the motor continues to run until the tripping arm 55 strikes the trip 55 171 which cuts off the current and also operates the reverse switch. Switches 16 and 17 are operated by the same kind of connections.

Carriage 5 then slides to a considerable distance past the switch 17 when it stops and the door is held open, the runners in the track affording sufficient friction to hold the counterbalanced door and to prevent any serious overthrow. The door remains open until the switch 18 is pushed 60 again, which starts the motor. The carriage then travels toward the left, trips the trip 171 which operates the combination cut-off and reverse switch which reverses the motor and automatically closes the circuit so that the push button can be released. The carriage travels until the trip arm 55 passes the trip lever 161 and cuts off the current and stops the motor. The motor and mechanism are then ready to open the door.

Should there be any obstruction, the clutch 75 automatically slips and no damage is done either

to the door or to the motor. The motor can be completely cut off by operating switch 19. It can also be controlled from the outside by the key switch 20, instead of the push button 18.

Having thus described my invention what I 80 claim as new and desire to secure by Letters Patent is:

1. In an overhead door control means, the combination of a flexible door made of horizontal hinged panels, a track therefor at the sides of the door and extending to a horizontal plane above the door, a pair of channel tracks centrally disposed and supported between the said door tracks, connected at their forward ends to a spreader above the door, and provided with a spreader at the inner ends, a carriage disposed between said central tracks with runners to slide thereon, an idler sprocket wheel supported on a suitable bracket on the spreader between the said tracks at the front, a driven sprocket wheel journaled on a suitable cross shaft at the inner end of said tracks, a sprocket chain secured to the front part of said carriage and disposed upwardly over the said idler sprocket wheel, thence rearwardly around the driving sprocket 100 wheel and secured by a spring to the rear of said carriage, a driven gear supported on the sprocket wheel shaft and having a clutch face thereon, a corresponding clutch member secured to the said sprocket wheel with a friction disk 105 interposed, a compression spring on the said sprocket wheel shaft urging the said sprocket wheel into contact to close the said clutch, an adjusting nut for regulating the pressure on the said clutch, whereby the resistance to the door 110 will cause the said clutch to slip, and an electric motor with reduction gear to drive said gears.

2. In an overhead door control means, the combination of a flexible door, a track therefor at the sides of the door and extending to a horizontal plane above the door, a pair of channel tracks centrally disposed and supported between the said door tracks, a carriage disposed between said central tracks having runners to slide thereon, an idler sprocket wheel supported between the said tracks at the front, a driven sprocket wheel journaled on a suitable cross shaft at the inner end of said tracks, a sprocket chain secured to the front part of said carriage and disposed upwardly over the said idler sprocket 120 wheel, thence rearwardly around the driving sprocket wheel and secured by a spring to the rear of said carriage, a driven gear supported on the sprocket wheel shaft and having a clutch face thereon, a corresponding clutch member secured to the said sprocket wheel, a compression spring on the said sprocket wheel shaft urging the said sprocket wheel into contact to close the said clutch, and an electric motor 125 having reduction gear to drive said gears.

3. In an overhead door control means, the combination of a flexible door, a track therefor at the sides of the door and extending to a horizontal plane above the door, a pair of channel tracks centrally disposed and supported between the said door tracks, a carriage disposed between said central tracks having runners to slide thereon, an idler sprocket wheel supported between the said tracks at the front, a driven sprocket wheel journaled on a suitable cross shaft at the inner end of said tracks, a sprocket chain secured to the front part of said carriage and disposed upwardly over the said idler sprocket 140 wheel, thence rearwardly around the driving sprocket wheel and secured by a spring to the 145 150

- rear of said carriage, a driven gear supported on the sprocket wheel shaft and having a clutch face thereon, a corresponding clutch member secured to the said sprocket wheel, a compression spring on the said sprocket wheel shaft urging the said sprocket wheel into contact to close the said clutch, an alternating current electric motor supported at the inner ends of said track, electric connections leading thereto, a cut-out switch and push button switch for controlling the same, automatic cut-off switches having a trip means adjustably secured to the said track, and a trip arm on the carriage for tripping the said cut-off switches. 80
- 10 4. In an overhead door construction, the combination of a door, means to open and close the same comprising suitable channel shaped tracks for operating therewith, a carriage having a trip arm adapted to travel on said tracks, an electric motor supported by said tracks, conductors leading to said motor disposed in a channel associated with said tracks, a cover for the said channel, flexible strips for retaining the said cover in place, automatic trip switches in boxes secured to the said track to be actuated by the trip arm, and closure plates secured to the said switch boxes for closing the said channel. 85
- 15 5. In an overhead door construction, the combination of a door, means to open and close the same comprising suitable channel shaped tracks for operating therewith, a carriage having a trip arm adapted to travel on said tracks, an electric motor supported by said tracks, conductors leading to said motor disposed in a channel associated with said tracks, a cover for the said channel, flexible strips for retaining the said cover in place, automatic trip switches in boxes secured to the said track to be actuated by the trip arm. 90
- 20 6. In an overhead door construction, the combination of a door, means to open and close the same comprising suitable channel shaped tracks for operating therewith, a carriage having a trip arm adapted to travel on said tracks, an electric motor supported by said tracks, conductors leading to said motor disposed in a channel associated with said tracks, a cover for the said channel, flexible strips for retaining the said cover in place, automatic trip switches in boxes secured to the said track to be actuated by the trip arm. 95
- 25 7. In an overhead door construction, the combination of a door, means to open and close the same comprising suitable channel shaped tracks for operating therewith, a carriage having a trip arm adapted to travel on said tracks, an electric motor supported by said tracks, conductors leading to said motor disposed in a channel associated with said tracks, and automatic trip switches in boxes secured to said track to be actuated by the trip arm. 100
- 30 5. In an overhead door construction, the combination of a door, means to open and close the same comprising suitable channel shaped tracks
